UNITED STATES PATENT OFFICE.

ALBERT C. FISCHER, OF CHICAGO, ILLINOIS.

ROOFING CLEAT.

Application filed December 12, 1919. Serial No. 344,322.

To all whom it may concern:

Be it known that I, ALBERT C. FISCHER, a citizen of the United States, residing at Chicago, in the county of Cook and State 5 of Illinois, have invented certain new and useful Improvements in Roofing Cleats, of which the following is a specification.

One object of the present invention is to provide a cheap and efficient roofing cleat 10 adapted for securing and weatherproofing or fireproofing the union between a roofing surface and the marginal portion of a roofing member superposed thereon, to which end one feature of the invention consists 15 in providing a cleat formed partially or wholly of sheet metal fashioned to substantially conform to a plurality of faces of roofing material, and consisting essentially in a longitudinal plate adapted to overlie the marginal upper surface of the roofing member to be secured, together, with an offsetting portion extending from one side thereof in a position sufficiently near the perpendicular to adapt it to stiffen the plate and also 20 to extend across the edge of the secured roofing member toward the surface upon which the latter is to be held; the cleat preferably also comprising a flange extending beyond the offsetting portion and under- 25 lying the under surface, which flange may be either an integral portion of the metal of the cleat or an extension of weatherproof or fireproof material which is applied as an under facing to the cleat.

A further object of the invention is to provide for cementing the roofing cleat to the members with which it is to be associated, to which end another feature of the invention consists in providing a roofing cleat 40 with a cemented facing of flexible material, such, for instance, as roofing felt, which may in turn be cemented to the surfaces of the roof to which the cleat is to be applied; a subordinate idea in connection with this feature of the invention consisting in having the packing or cementing material extend beyond the metal for the purpose of securing a more flexible cementing edge.

Another object of the invention is to 50 adapt the improved cleat for manipulation and application in extended lengths, but to render the goods flexible for rolling or otherwise reducing the dimension of packages

of the goods, to which end a further feature 55 consists in subdividing the cleat into convenient lengths and applying it by asphaltic or other suitable cement to continuous lengths of the packing or facing material.

A further object is to adapt the cleat for use in connection with spaced sections of 60 roofing material, such as shingles or the like, and to adapt it to not only hold down the free end of a shingle but to bridge the distance between two spaced shingles and assist in supporting an overlying shingle 65 over such space, to which end another feature of the invention consists in providing the cleat with a length corresponding to the width of the shingle; a subordinate idea incident to this part of the invention 70 consisting in giving to the cleat, or a portion thereof, a vertical or offsetting dimension equivalent to the thickness of two shingles so that it may drop down from the upper surface of one layer or shingle to the upper 75 surface of the second layer below, and so be adapted to form a weather barrier across the space between the two shingles and immediately beneath the edge of the bridging shingle. Additional subordinate ideas incident to this part of the invention consist 80 either in limiting the metal portion of the cleat in length to the space between two shingles and having additional parts thereof composed of the flexible roofing material 85 fashioned to conform to two different levels of roofing members, or else having the metal portion of the cleat supply both the bridging and weather barrier portions.

The invention will be fully understood 90 upon reference to the accompanying drawings, in which a number of different embodiments are shown by way of illustration.

In said drawings—

Figure 1 is a perspective view of a section of roofing in which two different types of cleat are embodied; and Figures 2 and 3 are perspective views showing the respective types of cleat employed in Figure 1.

Figures 2^a and 2^b are modifications of the 100 type of cleat shown in Figure 2.

Figure 4 is a perspective view showing a modification of the combined bridging and weather bar type of cleat.

Figure 5 shows a form of cleat which 105 serves the combined purpose of holding

down the intermediate or bridging portion of a shingle and affording a weather bar for the space beneath the same.

Figure 5^a shows a modification of the combined cleat and anchoring seal shown in Figure 5.

Figure 6 is a view showing a section of roofing to which is applied the form of cleat shown in Figure 5.

10 Figures 7 and 8 are, respectively, a perspective view and a section on the line 8—8 of Figure 7 showing a modification of the combined hold-down cleat and weather bar; and

15 Figures 9 and 10 show two forms of continuous sealing cleats in which the metal elements are subdivided into units.

Figure 11 is a view illustrating the method of packaging adhesive backed offset cleats with felt underfacing and adhesive of lasting masticity.

A represents shingles applied to a roof in known manner, with the shingles of one layer breaking joints with those of another 25 in order to cover the spaces between shingles. According to the present invention the shingles are laid with very wide spaces B between their opposed longitudinal edges, and the shingles A have their free ends provided with securing and strengthening 30 cleats C. Each cleat is formed with an upper plate c¹ which lies along the upper surface of a shingle adjacent its free end, and with an offsetting portion c² corresponding substantially to the thickness of 35 the shingle and extending toward the surface of the next lower series of shingles, where it may be provided with a bearing plate c³. According to Figure 2 the plate c³ constitutes an integral extension of the offset c². This feature of the invention, however, may be realized with good results by forming the plate c³ of an extension c^{3'} of 40 roofing felt, felted asbestos, or the like, as shown in Figure 2^a wherein the metal portion of the cleat terminates with the offsetting portion c².

E (Figures 5 and 6), E' E^x (Figures 2^a, 2^b, 5^a, 9 and 10), and E² (Figures 4, 7, and 8) 50 represent anchoring, sealing weatherproofing, or fireproofing strips to which the cleats are secured in different ways and in different relations, preferably by means of cement, and through means of which the cleats may readily be cemented to the roofing members and thus adapt the cleats to better seal the joints between the members and prevent weather elements or fire from being driven up beneath overlapping portions.

60 According to Figures 2^a, 2^b, 4, 5^a, 9 and 10 the anchoring strip E' merely follows the contour of the cleat and constitutes a facing for the latter. In Figures 5 and 6 the strip E is so related to the cleat that its portion 65 corresponding to the lower level may enter

between the upper face of a lower roofing surface and the under face of an upper member lapped thereon and thus become a cementing strip between overlapping parts; while in Figures 4, 7, and 8 it serves to 70 weather-proof the bridging space as herein-after described.

Cleats C are preferably cemented to the shingles A so that they are adapted to not only hold down the free ends of the shingles 75 when secured by nails through the perforations c⁴ but to sustain the shingles, particularly where they bridge the space between overlapped shingles. This permits the shingles to be spaced at much greater 80 distances apart, and economizes in the quantity of roofing material used, at least sufficient to pay for the cleats.

An important advantage arising from the use of cleats C in the particular relation to shingles herein described is that the cleat may conveniently embody the additional feature of a weather bar c⁵ or c⁶ (Figures 3 and 4), consisting of a further depression of a portion of the bearing plate c³ to fill the 90 space between shingles immediately beneath the cleat, and thus prevent wind and rain from blowing up under the shingles.

In Figure 3 the weather bar is provided by depressing a portion c⁵ of the plate c³; whereas in Figure 4 it is provided by cutting a lip c⁶ out of the plate c³ and permitting it to depend as an apron.

According to Figures 5 and 6 the hold-down cleat and weather bar may involve a 100 metal portion c⁷ which in length corresponds merely to the space between two shingles, and this will have its offsetting portion c⁸ substantially equal to a double shingle thickness so that it extends from the upper surface of one shingle across the end of such shingle and across the side edges of two spaced shingles beneath, where it meets an anchoring strip E to which it is cemented. The anchoring strip E, as suggested in 105 Figure 6, will be indefinite in length and will underlie a series of shingles and be cemented to them preferably in a manner to unite the intermediate portions of overlapped shingles. The metal cleat c⁷ c⁸ may 110 be secured to the anchoring strip E, as shown in Figure 5, by providing the latter with an upturned tab e to which the offset portion c⁸ of the cleat is cemented. The perforation c⁴ in the combined cleat and weather bar c⁷ c⁸ adapts it to further secure 115 the shingle.

As shown in Figures 7 and 8 the facing of felt may extend beyond the ends of the combined cleat and weather bar c⁷, as shown 125 at E² and may be stepped from the upper to the lower level of overlapped roofing members and cemented to both so as to secure portions of the free edges of the shingles lying beyond the cleat; the weather bar c⁸ 130

or apron being permitted to depend, as shown in Figure 8, in this form. The facing strip E^2 is also extended down behind the apron or bar c^8 and may have its extended edge E^2 deflected outward beneath the lower edge of said apron or bar to secure a more effective seal of the joint.

In all the forms, cementing of a sheet metal cleat to a strip of fabric through means of asphaltic cement will be found to firmly and intimately unite metal to fabric and adapt the composite material thus produced to remain assembled and be freely manipulated without danger of separation.

15 As suggested in Figure 8, the nail bosses c^4 permit the accumulation of the cementing material in their hollow undersides, and thereby automatically seal the securing nails when driven in.

20 The improved form of cleat is not limited in its application to roofing members subdivided into shingles, but as suggested in Figures 9 and 10 may be used in securing the lapped edges of continuous roofing sheets.

25 A', A'. For this purpose the cleat will be subdivided into sections cemented upon a strip E' and having a plurality of nail holes c^4 , the length of cleat being as large as practicable without rendering inconvenient the 30 flexing or folding of the strip for shipment; or the cleat may be subdivided into relatively shorter units c^{10} as shown in Figure 10, each with a single nail hole c^4 . In either case the cleats will be secured to the strip by cementing through means of asphalt or other equivalent adhesive.

35 Preferably in the form of cleats shown in Figures 1, 2 and 3 will be provided with a facing E' or E^2 of felt or like material to which they are firmly cemented, and which will in turn be cemented to the roofing members to which the cleat is applied. The adhesive for this purpose may be in the form of a cement of lasting masticity applied to the goods in manufacture and protected either by placing together opposed mastic faces of two strips of the goods, reversed in position to bring the elevated portion of one faced cleat against the depressed portion of another cleat, as illustrated in Figure 11, or by application to the mastic of a non-absorbing thin protecting sheet that can be removed to expose the adhesive and discarded at the time of applying the cleat to the roof.

55 I claim:

1. A roofing cleat having an elongated substantially flat plate with a downwardly disposed offsetting portion lending stiffness thereto; said plate having means adapting it to be nailed in position; a portion of said offsetting surface being extended beyond the rest to adapt it to provide a weather bar for the space between two separated portions of overlapped roofing.

60 2. A roofing cleat having an elongated

plate adapted to overlie the roofing member at one level, an offsetting portion extending to another level, and a weather bar forming a continuation of said offsetting portion beyond said other level.

70

3. A roofing cleat having an elongated substantially flat plate with a downwardly disposing offsetting portion lending stiffness thereto; said plate having means adapting it to be nailed in position; and said offsetting portion carrying a bearing plate in position to rest upon a lower level of roofing surface, a portion of said bearing plate being displaced to provide a weather bar.

75

4. In combination with a shingle roof, a cleat adapted for attachment to the free end of a shingle, and having a portion extending downwardly into the space between two shingles of a lower level.

80

5. In shingle roofing, cleats adapted for attachment to the free ends of bridging shingles and having each a portion extending downwardly through the space between two bridged shingles and there provided with hold-down means for engaging beneath said bridged shingles.

85

6. In combination with felt roofing shingles laid in overlapping rows with spaces between the shingles of a row, combined hold-down and space-closing means carried by the bridging portions of overlapping shingles, and each including in its construction a portion extending from the bridging shingle downwardly past the edges of bridged shingles, substantially corresponding in width to the space between the latter, and provided at its lower end with hold-down means for engaging beneath said bridged shingles.

90

7. In combination with felt roofing shingles, laid in overlapping rows with spaces between the shingles of a row, combined hold-down and space-closing means carried by the bridging portions of overlapping shingles, and each including in its construction a portion extending from the bridging shingle downwardly past the edges of bridged shingles, substantially corresponding in width to the space between the latter, and provided at its lower end with hold-down means for engaging beneath said bridged shingles; said downwardly extending portion and hold-down means comprising felt deflected from the plane of the downwardly extending portion to that of the hold-down portion.

95

8. A roofing cleat fashioned to conform to two faces of roofing material in different planes, and having a facing of fibrous material thereon in position to be cemented to both said faces.

100

9. A roofing cleat comprising an overlying plate and an offsetting portion and having a facing of fibrous material upon both said plate and said offsetting portion.

105

10. A roofing cleat having an overlying plate, an offsetting portion, and a bearing plate beyond said offsetting portion, and having a facing of fibrous material underlying both said plates and the offsetting portion.
11. A roofing cleat fashioned to conform to two different surfaces of roofing material, and having a facing of fibrous material thereon in position to be cemented to both said surfaces, the exposed side of the fibrous material being coated with a sticky mastic to render it self-adhering.
- 10 12. A roofing cleat adapted to overlie a roofing member for holding down the same; said cleat being constructed with a nailing boss and having a fibrous material cemented to the face thereof beneath said nailing boss, in position to lie upon the surface upon which the cleat is laid.
- 15 13. A roofing cleat adapted to overlie a roofing member for holding down the same; said cleat being constructed with a nailing boss and having a fibrous material cemented to the face thereof beneath said nailing boss, in position to lie upon the surface upon which the cleat is laid; the nailing boss being hollow and having its hollow filled with a mastic substance.
14. As a new article of manufacture, roofing shingles having cleats attached to 30 the upper surfaces of their free ends and carried by said shingles independently of the attachment of the shingles in use.
15. As a new article of manufacture, a roofing cleat having a fibrous material cemented to the under surface thereof, and said fibrous material having its exposed surface coated with a sticky mastic.
16. As an article of manufacture, roofing cleats constructed with facings of fibrous 40 material, coated with adhesive of lasting masticity, and separably assembled with their adhesive faces in contact and mutually protecting relation.
17. As an article of manufacture, roofing 45 cleats constructed with faces of fibrous material and with adhesive of lasting masticity upon the outer surfaces of said faces, different longitudinal portions of a cleat being offset, and said cleats being assembled in 50 pairs, reversed in position, and their adhesive faces separably adhered together.

Signed at Chicago, Illinois, this 28th day of November, 1919.

ALBERT C. FISCHER.
